FREEMAN H. OWENS, OF NEW YORK, N. Y.

SOUND SHUTTER

Application filed February 3, 1927. Serial No. 135,632.

My invention relates to the recording and reproduction of sound photographically and comprises means for closing the slit through which the light passes in such recording or reproducing processes, either automatically or through the control of the operator.

It will be understood that in the reproduction of a sound record which has been photographed on film, the film is moved at a constant speed past a narrow slit over which the sound record passes. A light of constant intensity is placed so that its rays pass through this slit and through the sound record as it moves past the slit. As this sound record varies in density at the point of passing the slit, the light rays from the lamp passing through the sound record likewise vary in intensity, exactly as the sound record varies. This varying light acts upon a photo electric cell which sets up electric impulses in accordance with such light variations, which impulses after amplification in any well known manner are passed to a loud speaker or other sound reproducing instrument where the sounds photographed on the film are rendered distinct and audible.

Naturally the amplification required to render the electric impulses given off by the photo electric cell strong enough to operate the loud speaker is very great. Consequently, all electric impulses set up by the photo electric cell, whether due to the light variations caused by the sound record or to the imperfections in the film, are greatly amplified and are audible through the loud speaker. In fact, the film itself varies in color and light transmitting properties to such an extent that when no sound record is passing the slit, a loud hissing or "frying" noise is audible through the loud speaker. Of course, when a sound record is passing the slit, the sound itself reproduced in the loud speaker being of much greater volume overcomes the hissing noise produced by the film itself and the latter is therefore not noticeable. There are times, however, when there is an interruption of the sound record for one purpose or another and during these interruptions the hissing noise through the loud

speaker is decidedly noticeable and objectionable.

In addition to this, there are of a necessity a number of splices in the sound film and at the points of splicing there is always a transparent line caused from scraping the film, as well as considerable variation in the density of the film itself, which, as it passes the slit, causes a marked variation in the light which reaches the photo electric cell, and in the case of the transparent line, which allows a flash of light to pass through to the photo electric cell, creates a loud "booming" noise in the loud speaker caused by the amplification of the electric impulses thus set up by the photo electric cell.

It is highly desirable therefore that some means be provided for eliminating this hissing noise caused by the film between sound records and the noise produced by the splices of the film. The accomplishment of these purposes forms some of the objects of my invention.

Also, it should be explained briefly, there are occasions during the recording of sound photographically when it is desirable to close the optical slit to the passage of light to the film. As is well known in the art, the recording of sound on sensitized film involves the changing of the sound waves to electric impulses, and imposing said impulses on the electric current which supplies the recording lamp. This recording lamp is so made as to be very sensitive to variations in current and therefore the intensity of the light from said lamp varies exactly in accordance with said electric impulses. This light of varying intensity is then passed through an optical slit past which, on the side opposite the lamp, a photographic film is moved at a constant speed. There is thus photographed on the sensitized film a sound record varying in density exactly in accordance with the sound waves. My invention therefore includes among its objects the provision of means for shutting off the passage of the light to the film during such recording operation.

More specifically, I have provided a shutter device adapted to either cut off the modulated light passing to the photo-electric cell

in a reproducing operation, or cut off the actinic light passing to the film in a recording operation.

This shutter may be automatically controlled by the film itself or it may be under the control of the operator under certain circumstances.

This device is particularly useful during the recording of sound for a motion picture, the picture film of which has already been made. In such recording process, the picture film is projected to the screen and the sound, for instance music, is recorded simultaneously and synchronously with the projection of the picture, said sound record being photographed on a separate strip of sensitized film. After the sound has been recorded, it is necessary that the sound film and the picture film be matched foot for foot and frame for frame for printing together on a single film for reproduction. In order to assist the editor in matching the sound film and the picture film, I provide means including my improved shutter for controlling the sound record in connection with the picture film. The details of this controlling device will be described later.

I also provide means whereby the shutter is controlled either by the picture film during the recording of the sound record, or by the operator or other independent party, as desired.

Referring now to the drawings wherein like reference numerals indicate like parts:

Figure 1 is a front view illustrating the operation of my shutter during the reproduction of a sound film.

Figure 2 is a side view thereof.

Figure 3 is a diagrammatic view illustrating the use of my shutter during the recording of a sound record and illustrating the method of control by either the picture film in connection with which the sound is being recorded, or by independent operation.

Figure 4 is a detail view of my shutter device.

Figure 5 is a detail view of portions of a length of film formed for use with my shutter device.

Figure 6 is a view partly in section and partly diagrammatic illustrating the use of my shutter in connection with the reproduction of sound photographically recorded.

I will first describe my invention in connection with the reproduction of sound.

The reference numeral 1 indicates a support to which is secured as by the screws 2 a slideway 3 provided with grooves 4 for slidably receiving a member 5. This member 5 is hollowed as at 6 and in alignment with the hollow portion 6 and on the opposite side of the support 1, preferably secured thereto by the same screws 2, is a tubular member 6a adapted to receive a lamp 6b of constant intensity. Also mounted in the

tubular member 6a are suitable condenser lenses 6c through which the light from the lamp 6b passes and is focused to the opposite end of the hollow member 5 for a purpose to be described.

The member 5 is provided in its front face with an opening 7 around which is mounted a ring 8 projecting slightly beyond the face of the member 5. Mounted on the ring 8 for slight rotatable adjustment thereon is a slit holder 9 which may be secured in adjusted position to the member 5 by the screws 10. A slit member 11 preferably comprising a small prism, is suitably secured in the slit holder 9 at a point in alignment with the opening 7, whereby the light may pass therethrough. This slit member 11 is so positioned that one apex thereof lies flush with the front face of the slit holder 9 and it is through this narrow apex of the slit member that the light passes. The film 12 is moved in any suitable manner over the face of the slit holder 9 and in engagement with the slit member 11. Film 12 carries a sound record 12a which moves past the slit member 11 thus controlling the intensity of the light passing through the film to the photo-electric cell C.

As this varying light is received by the photo-electric cell C, feeble electric impulses are set up therein corresponding to the variations in light intensity. These impulses are imposed upon an electric current supplied by the battery B and controlled by the potentiometer P. This modulated current is then amplified to the desired or practical degree by the vacuum tubes V, deriving their electric current from the filament battery F and the plate battery P. Three stages of amplification are shown, but it will be understood that more or less may be used if desired. Furthermore, it should be stated that the circuits or "hook-up" herein shown and described is illustrative only and in no sense limitative.

The amplified impulses are now passed to the loud speaker S where they are converted into sound waves and rendered audible.

As shown clearly in Figures 2 and 4, the member 5 is recessed as at 13 adjacent the slit holder 9 to provide a passage for the shutter 14 which may be pivoted to one of the screws 10 and one end 14a of which lies adjacent the slit member 11 between said slit member and the light source within the member 5. The opposite end 15 of the shutter 14 provided with a roller 16 engaging with the edge of the film 12 and riding thereon. The parts are so arranged that when the roller 16 is carried upon the edge of the film 12, the shutter 14 will be raised above the slit member 11 thereby permitting the light to pass through the film. The film 12 however is notched at predetermined intervals along its edge as at 17 whereby when one of these notches reaches the roller 16, the weight of

the shutter will cause the roller to drop into such notch, thereby permitting the end 14a of the shutter to drop down and cover the slit member 11 thus preventing the passage 5 of light therethrough. Obviously, the notches 17 may be of any desired length, that is, in order to cause the shutter to prevent the light reaching the photo-electric cell C at all times when there is no sound record to 10 be reproduced, or the notches may be very short and just sufficient to permit the dropping of the shutter 14 to cover the slit for an instant such as for example during the 15 passage of a splice 18 past the slit 11.

15 It will thus be seen that I have provided means for automatically controlling the passage of light through the film to the photo-electric cell during the reproducing of a sound film, such control being effected by the 20 film itself, thus doing away with the hissing or "booming" noise produced in the loud speaker during the time when no sound record is being produced and during the passage of the splices past the slit.

25 In Figure 3, I have illustrated the use of my invention for sound recording and wherein the reference numeral 19 refers to a support corresponding to that numbered 1 in the foregoing modification. Mounted on 30 this support 19 in a manner similar to that above described is a slit member 20 through which the recording light is adapted to pass to the film 21 which moves over the slit 20. Pivoted, as at 22 on the support 19 is the 35 shutter 23, one end of which lies adjacent the slit 20 and the opposite end of which is secured by link 24 to an armature 25 normally pulled away from the electro-magnet 26 by means of the spring 27.

40 The electric circuit of the magnet 26 includes the battery 28, a switch 29, a stationary contact 30 and a movable contact 31. The movable contact 31 is carried by one end of a lever 32 having a coil spring 33 acting 45 thereon to normally pull the contact 31 into engagement with the contact 30 thereby closing the circuit to the electro-magnet 26. The opposite end 34 of the lever 32 carries a roller 35 adapted to ride on the edge of a 50 picture film 36 thereby normally holding the contact 31 out of engagement with the stationary contact 30. The picture film 36 may be notched along its edge at predetermined points as at 37 whereby the roller 35 upon 55 dropping into one of said notches permits the closing of the contacts 30 and 31 and consequently the circuit of the electro-magnets 26 resulting in attracting the armature 25 to the magnet thus exerting a pull on the shutter 23 causing the same to move over and close the slit 20 thereby preventing the passage of light through said slit to the film 21.

Also included in the circuit of the electro-magnet 26 is a manually operable key 38 60 which may be operated to control the shut-

ter independently of the film 37. If desired, the switch 29 may be opened thereby eliminating the use of the contacts 30 and 31 and the key 38 may then be used for controlling the shutter 23. Or if desired, the key 38 may be used to supplement the operation of the shutter by the automatic means provided on the film 36.

70 From this construction, it will be understood that during the recording of sound on the film 21, which sound is appropriate to the picture film 36 in connection with which the sound record is being made, such recording is controlled either automatically by the picture film or manually by the operator as desired. The use of the notches 37 in the picture film is helpful to the editor who subsequently matches the sound film and the picture film for printing together, as before explained.

75 By the term "optical slit", I refer to any type of slit, for the passage of light. The prism type herein shown and described is intended as illustrative only.

80 Many changes in details of construction and operation will be apparent to those skilled in the art without departing from the scope of my invention. I do not limit myself, therefore, to the exact form shown other than by the appended claims.

85 I claim:—

1. In combination, a source of light, a film strip having a sound record thereon in the path of said light for varying the intensity of said light passing from said film in accordance with the sound record, an optical slit through which said light passes to said film, a splice connecting one film strip to a continuing film strip, one of said film strips being notched in advance of said splice, and shutter means operative by said notched film strip for interrupting the passage of said light to said film when said splice passes said optical slit.

100 2. In combination, a source of light, a film strip having a sound record in the path of said light, splices formed in said film strip, said film strip having notches in one of its edges adjacent each of said splices, an optical slit through which said light passes to said film, and shutter means for interrupting the passage of said light to said film, the operation of said shutter being controlled by the notches in the edge of said film as said splices approach said optical slit.

110 3. In combination, a source of light, a film strip having a sound record in the path of said light, said film strip having notches in one of its edges, a photo-electric cell for receiving the light passing through said film, an optical slit between said light and said film, and a shutter for interrupting the passage of light from the portions of said film which are adjacent to said notches to said photo-electric cell.

4. In combination, a source of light, a film strip having a sound record in the path of said light, said film strip having notches in one of its edges, a photo-electric cell for receiving the modulated light passing through said sound record, and a shutter for interrupting the passage of light from the portions of said film which are adjacent to said notches to said photo-electric cell.
- 10 5. In combination, a source of light, a film strip having a sound record in the path of said light, splices formed in said film, said film strip having notches in one of its edges in advance of each of said splices, an optical slit 15 through which said light passes to said film, and a shutter between said light and said optical slit, and electrical means operated by the said notches for actuating the said shutter for interrupting the passage of light 20 therethrough when said splices approach said optical slit.
6. In combination, a light, a film strip having a sound record in the path of said light, a splice connecting portions of said film, an 25 optical slit through which said light passes to said film, a shutter normally held out of the path of said light, and means on said film opposite said sound record for moving said shutter to interrupt the passage of said light 30 to said film when said splice approaches said slit.
7. In combination, a light, a film strip having a sound record in the path of said light, a splice formed in said film, an optical slit 35 through which said light passes to said film, a pivoted shutter normally held out of the path of said light by an edge of said film, and a notch on said film edge in advance of said splice whereby said shutter is operated to interrupt the passage of light to said film during the time interval that said splice is passing said slit.
8. In combination, a light, a movable film strip and a slit through which said light 45 passes, a splice in said film strip, a sound record on said film strip for modulating the light passing therethrough, a photo-electric cell for receiving said modulated light, a shutter for automatically interrupting the 50 passage of said modulated light to said photo-electric cell, and means for operating said shutter during the passage of said splice past said slit.
9. In combination, a light, an optical slit 55 in the path of said light, a film strip having a sound record thereon through which said light passes from said slit, a splice in said film, a shutter for interrupting the passage of light through said film, and means on 60 said film adjacent said splice for operating said shutter to interrupt said light during the movement of said splice past said slit.

FREEMAN H. OWENS.
